UNITED STATES PATENT OFFICE.

WESLEY B. SHERMAN, OF SIOUX CITY, IOWA.

AXLE-CUTTER.

SPECIFICATION forming part of Letters Patent No. 622,548, dated April 4, 1899.

Application filed March 29, 1897. Serial No. 629,685. (No model.)

To all whom it may concern:

Be it known that I, WESLEY B. SHERMAN, a citizen of the United States, residing at Sioux City, in the county of Woodbury and State of Iowa, have invented certain new and useful Improvements in Axle-Cutters; and I do hereby declare the following to be a full, clear, and exact description of the invention, such as will enable others skilled in the art to which it appertains to make and use the same.

The invention relates to improvements in axle-cutters.

The object of the present invention is to improve the construction of axle-cutters and to provide a simple, inexpensive, and efficient one, adapted to be readily carried from place to place and capable of operating on an axle without necessitating the removal of the same from the vehicle.

The invention consists in the construction and novel combination and arrangement of parts, as hereinafter fully described, illustrated in the accompanying drawings, and pointed out in the claim hereto appended.

In the drawings, Figure 1 is a plan view, partly in section, of an axle-cutter constructed in accordance with this invention and shown applied to an axle. Fig. 2 is a rear elevation of the same. Fig. 3 is a detail view of the cutting-disk, illustrating the arrangement of the cutters.

Like letters of reference designate corresponding parts in all the figures of the drawings.

B designates a clamping-sleeve adapted to be arranged on an axle A, as illustrated in Fig. 1 of the accompanying drawings, and it is rigidly secured to the said axle by a plurality of radially-arranged clamping screws or bolts b, mounted in threaded perforations of the sleeve and adapted to project into the central passage or opening of the same. The clamping screws or bolts b are preferably arranged in two annular series, located adjacent to the ends of the sleeve and adapted to enable the sleeve to be properly positioned with relation to the spindle. The sleeve is provided at a point between its ends with a substantially triangular plate b', having enlargements b² at the ends of its arms. This plate b' is connected by longitudinal bolts b⁴ with a corresponding similar-shaped plate b³,

provided with an internally-screw-threaded sleeve b⁵, into which screws an exteriorly-screw-threaded sleeve b⁶. The sleeve b⁵, which is formed integral with the front triangular plate b', extends outward therefrom, and the sleeve b⁶, which is arranged within the sleeve b⁵, is provided at its outer or front end with an inwardly-extending annular flange b⁷, forming an interior shoulder. The outer end of the sleeve b⁶ is also provided with an outwardly-extending annular flange b⁸, having thumb-pieces b⁹, adapted to be readily grasped by the operator when it is desired to screw the sleeve b⁶ into the sleeve b⁵ and feed a cutter C.

The cutter comprises a disk or head and a shaft c, journaled in the sleeve b⁶ and provided with an annular shoulder c', which abuts against the annular flange b⁷, whereby the shaft c is caused to move inward when the sleeve b⁶ is screwed inward. The outer end c² of the shaft c is screw-threaded and receives a crank-handle D, by means of which the shaft is rotated.

The inner face of the cutter-head is provided at diametrically opposite points with enlargements or studs c³ and c⁴, which are of different heights, so as to project different distances from the face of the cutter-head for bringing the knives c⁵ and c⁶, which are mounted at the ends of the studs or enlargements, in different planes to engage the end of the axle proper and the end of the journal or bearing portion of the same. The knives c⁵ and c⁶ are mounted in transverse grooves c⁷, cut in the tops of the studs or enlargements c³ and c⁴, and are adjustably held in position by clamping screws or bolts c⁸, which screw into the said studs or enlargements. The screws or bolts carry nuts c⁹, which bear upon the tops or outer faces of the cutters c⁵ and c⁶, which have their inner ends beveled, as shown.

When an axle is to be recut because of the wearing away of its inner shoulder, which makes the journal portion of said axle longer than the boxing in a wheel, the sleeve B is adjusted upon and securely clamped to the journal portion of the axle and the knives c⁵ and c⁶ are moved up in proper position for cutting the extremity of the axle and the outer end of the journal or bearing portion,

as clearly shown in Fig. 1 of the drawings. The crank-handle D is then operated to cause the knives to revolve around the axle, and as the cutting proceeds the knives are gradually moved forward by screwing the feeding-sleeve b⁶.

The invention has the following advantages: The axle-cutter, which is simple and comparatively inexpensive in construction, is 10 portable and may be readily carried from place to place to cut axles of different vehicles, and it does not necessitate the removal of the running-gear from a vehicle, as a single wheel may be removed and the device applied 15 to the axle while the remainder of the vehicle remains intact.

Changes in the form, proportion, and minor details of construction may be resorted to without departing from the spirit or sacrificing 20 any of the advantages of this invention.

What I claim is—

In a device of the class described, the combination of a clamping-sleeve, a substantially

triangular frame b' centrally connected with the sleeve and located at a point between the 25 ends thereof, the outer triangular frame provided with an outwardly-extending integral sleeve having interior screw-threads, bolts connecting the said frames, an exteriorly-threaded sleeve adjustably fitted therein and 30 provided at its outer end with inwardly and outwardly extending flanges, the outwardly-extending flanges being arranged to be grasped by the operator, a cutter having a shaft arranged within the exteriorly-threaded 35 sleeve and provided with a shoulder abutting against the inwardly-extending flange thereof, and means for rotating the shaft, substantially as described.

In testimony whereof I have signed this 40 specification in the presence of two subscribing witnesses.

WESLEY B. SHERMAN.
